UNITED STATES PATENT OFFICE.

GEORGE W. PEIFER, JR., AND ROBERT JOHNSTON, OF WILKES-BARRÉ,
PENNSYLVANIA.

TORPEDO-PLACER.

SPECIFICATION forming part of Letters Patent No. 462,992, dated November 10, 1891.

Application filed July 17, 1891. Serial No. 399,864. (No model.)

To all whom it may concern:

Be it known that we, GEORGE W. PEIFER, Jr., and ROBERT JOHNSTON, citizens of the United States, residing at Wilkes-Barré, in the county of Luzerne, State of Pennsylvania, have invented certain new and useful Improvements in Torpedo-Placers, of which the following is a specification, reference being had therein to the accompanying drawings.

10 This invention relates to certain new and useful improvements in torpedo-placers; and it has for its objects, among others, to provide an improved device of this character which shall be simple, cheap, durable, and efficient in operation and which shall hold the torpedo upon the rail in such a way as to insure its lying close thereupon and not tilting as the placer is removed. It has for a further object to provide an improved clamp for holding

20 the torpedo upon the rail.

We provide pivoted jaws for holding the torpedo, which jaws are operated by the downward movement of the handle to release the torpedo.

25 Other objects and advantages of the invention will hereinafter appear, and the novel features thereof will be specifically defined by the appended claims.

The invention is clearly illustrated in the accompanying drawings, which, with the letters of reference marked thereon, form a part of this specification, and in which—

30 Figure 1 is a view, partly in side elevation and partly in longitudinal section, of our improved device. Fig. 2 is a central longitudinal section through the device at right angles to Fig. 1. Fig. 3 is a cross-section through a rail with the torpedo thereon.

Like letters of reference indicate like parts throughout the several views.

40 Referring now to the details of the drawings by letter, A designates the torpedo, which may be of the usual construction, except as regards the arms or clamps A', which are of the form shown in Fig. 3—that is, arranged to embrace the rail A² with the free ends of the arms bent upon themselves, as shown at a, with the ends extending at an angle, as seen in Fig. 3, so as to bear upon the under face 45 of the tread of the rail and prevent cocking up of the torpedo.

B is a socket-plate, formed at its lower end with a chuck b to hold the torpedo, and this chuck is provided with a recess or chamber for the reception of a spring B', adapted to 55 bear upon the torpedo and force it downward when not otherwise restrained.

C is the handle held in the socket-piece, and which handle may be of any desired length and shape. The upper end of the 60 socket-piece is surrounded by the spring D, which finds its points of resistance against the flange or shoulder c at this upper end and the flange or shoulder c' at the upper end of the sleeve E. This sleeve has longitudinal 65 slots e and terminates in the bumpers F, as seen best in Fig. 2. These bumpers are of such length as to rest upon the upper face of the rail when the torpedo is being placed.

G are jaws pivoted at g to the socket-piece 70 and their lower ends hooked or otherwise formed to engage beneath the bottom of the torpedo, as seen in Fig. 2. The upper ends are tapered or inclined outward, as shown at g' in Fig. 2, and extend into the slots e of the 75 sleeve, the lower walls of which are correspondingly inclined or tapered, as seen in said Fig. 2.

Extending parallel with the pivots of the jaws is a pin H, which is fast to the socket- 80 piece, and at its outer end works in a longitudinal slot g² of the outer sleeve, as seen in Figs. 1 and 2.

The operation is apparent and simple. The 85 torpedo is held in the placer, as seen in Fig. 2, with the hooked ends of the jaws beneath the torpedo and the sleeve at its lowest position. When it is desired to place the torpedo upon the rail, it is manipulated by the handle, and the lower ends of the bumpers rest upon 90 the rail, the jaws holding the torpedo until pressure is applied upon the upper end, when the bumpers being forced against the rail the sleeve is forced upward, and in its upward movement the incline of the lower walls of its 95 slots presses against the outer faces of the inclines of the upper ends of the jaws and forces the said upper ends inward and their lower ends outward away from the torpedo, when the spring B' forces the torpedo down upon 100 the rail and its arms embrace the rail, as seen in Fig. 3. As soon as pressure is removed

from the handle the parts assume their normal position, and a new torpedo may be placed in the device ready for future use. The lower portion of the socket-piece is tapered upon 5 opposite sides, as seen in Fig. 2, for the better working of the pivoted jaws.

Modifications in detail may be resorted to without departing from the spirit of the invention or sacrificing any of its advantages.

o What we claim as new is—

1. The combination, with the torpedo-holder, of the pivoted jaws and the movable sleeve adapted to actuate the jaws, as set forth.

2. The combination, with the sleeve having 15 bumpers, of the pivoted jaws arranged to engage beneath the torpedo and to be actuated by the movement of the sleeve, as set forth.

3. The combination, with the socket-piece and the movable sleeve having slots, of the 20 pivoted jaws having outwardly-inclined ends working in said slots, as set forth.

4. The combination, with the socket-piece and the chuck with its spring, of the movable slotted sleeve, the lower walls of the slots being inclined, and the pivoted jaws having 25 their upper ends inclined outward and into said slots, as set forth.

5. The combination, with the socket-piece, its handle, and spring, of the movable slotted sleeve, the pivoted jaws having outwardly-inclined upper ends working in said slots, and the spring at the lower end of the socket-piece to bear upon a torpedo, substantially as shown and described.

In testimony whereof we affix our signatures 35 in presence of two witnesses.

GEORGE W. PEIFER, JR.
ROBERT JOHNSTON.
